(57) **CLAIM**

An ornamental design for a mounting cap for a dispenser carrier, as shown and described.

DESCRIPTION

FIG. 1 is a perspective view of our invention; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a view thereof similar to FIG. 2, but showing the environment of a clip latch in an alternative, open position; FIG. 9 is another perspective view thereof, but showing the environment of two possible apertures at different positions (three o'clock and nine o'clock instead of twelve o'clock and six o'clock); FIG. 10 is a view similar to FIG. 2, but with the FIG. 9 environment; and, FIG. 11 is a view similar to FIG. 4, but with the FIG. 9 environment. The dotted line representations of apertures in FIGS. 1-6 and 8-11, clip latching structures in FIGS. 1-3, 5, 6 and 8-11, and of internal structure in FIG. 7, are for purposes of illustration only and form no part of the claim.
